Patented Apr. 18, 1922.

UNITED STATES PATENT OFFICE.

JAY A. HEIDBRINK AND BURT J. CLARK, OF MINNEAPOLIS, MINNESOTA.

ANÆSTHETIZING MACHINE.

1,412,866.

Specification of Letters Patent. Patented Apr. 18, 1922.

Application filed August 6, 1917. Serial No. 184,652.

To all whom it may concern:

Be it known that we, JAY A. HEIDBRINK and BURT J. CLARK, citizens of the United States, residing at Minneapolis, in the county of Hennepin and State of Minnesota, have invented certain new and useful Improvements in Anaesthetizing Machines, of which the following is a specification.

Our invention relates to anæsthetizing machines and has for its object to provide means for controlling the flow of gas to a patient and for insuring its delivery under a maximum pressure and in a thoroughly purified condition.

The full objects and advantages of our invention will appear in connection with the detailed description thereof and are particularly pointed out in the claims.

In the drawings, illustrating the application of our invention in one form,—

Fig. 1 is a part sectional elevation view of a portion of a gas delivering apparatus. Fig. 2 is a sectional elevation view of the relief valve mechanism employed in connection with our invention. Fig. 3 is a sectional view of a part of the gas-introducing connections.

As illustrated, a portion of the supporting head of the machine is shown at 10, having arms 11 and 12 through which extend ducts 13 and 14. The ducts 13 and 14 communicate with an orifice 15 controlled by a valve member 16 that is normally held seated to cover the lower end of orifice 15 by means of a spring 17. The spring and valve member, which is in the form of a cylindrical plunger, is housed in a tubular extension 18 that is closed by a cap 19 threaded into extension 18, and which cap provides means for regulating the force exerted by spring 17. A yoke piece 19' extends through apertures in the head 10 and engages with its feet the valve plunger 16 and with its top a diaphragm 20 which is supported within a chamber 21 formed in a discoidal easing 22, said chamber being in communication with the space surrounding the discharge end of the orifice 15. The easing 22 is provided with a central extension 23 in which is a powerful coil spring 24 which is held in engagement with a seat 25 upon the diaphragm 20 and over the yoke 19' by means of a plunger 26 which is controlled by a handscrew 27 threaded into the upper portion of extension 23. The spring 24, through diaphragm 20 and yoke member 19',

tends to force plunger 16 outwardly against the force of spring 17 to open the valve. On the other hand, the pressure of gas admitted into chamber 21 upon the extended surface of diaphragm 20 tends to resist the force of spring 24 and neutralize its action, thus permitting spring 17 to force valve plunger 16 into closing position. Turning of screw 27 will increase or decrease the pressure of spring 24 and therefore admit gas to chamber 21 by greater or less pressure, as may be desired. The gas comes from containers 30 in which the gas is stored at very high pressure. Containers 30 are suspended in apertures 31 and 32 in arms 11 and 12, respectively, and have side portions 33 adapted to be forced into sealing engagement with circular disks 34 having a neck 35 seated in the body 10 so that the aperture 36 therein forms a continuation of aperture 13 (or 14). The face of disk 34 is preferably corrugated as indicated at 37, which receives corresponding corrugations on the side 33 of container 30 and a set screw 38 threaded into the end of arm 11 holds these parts in gas-tight engagement. A hand valve 39 controls the flow of gases to the apertures 36, 13.

Threaded within the disk 34, and so that its interior bore 40 forms a continuation of passageway 36, is a nipple 41 having on the end thereof a fine wire strainer 42. This nipple seats within an aperture indicated in dotted lines at 43 in Fig. 1. All of the gas which passes to chamber 21 must pass through this strainer. Fine scales which may form on the interior of containers 30 are caught by this strainer and prevented from passing into the passageways and the valve seat and thereby interfering with the operation of the mechanism. The nipple 41 also provides means for receiving and guiding the neck of container 30 and a container head thereof.

The gas from chamber 21 passes through a connector tube 44 to the mixing and administering chambers and passageways, which form no part of our present invention and need not be described here. It will be apparent that the purified and strained gas reaches and leaves the chamber 21 at very much reduced pressure over that to which it is subject in container 30. It is, however, essential that the pressure of the gas in chamber 21 in going through passageway 44 shall in no instance be greater than a de-

sired maximum limit. To insure against any possibility of gas going to passageway 44 at a greater pressure than this maximum through faulty operation or other causes, we 5 provide the relief valve 50, which, as shown in Fig. 2, comprises the outer casing 51 having a multiplicity of lateral apertures 52 leading through ducts 53 to a valve seat 54 formed on the end of a tubular head 55 10 which has the threaded extended end 56 thereof screwed into the casing 22. Upon valve seat 54 is a valve plunger 58 normally held in engagement with valve seat 54 by a spring 59, the force of which is adjusted by 15 a screw 60 threaded into the end of casing 51 and held in fixed position by a clamp nut 61.

The advantages of our invention will be apparent. A perfect reduction system is 20 employed whereby gas goes to the patient not only at a reduced pressure, but at a pressure which cannot go above a definite maximum even under faulty operation. The gas so delivered is moreover freed from scale or 25 other solid matter which might get under the valve closure and prevent accurate operation of the controlling mechanism.

We claim:

1. An anæsthetizing machine comprising 30 an apertured support, a socket piece held by said support and providing through the same a continuation of said aperture, a nipple removably carried by the socket piece and forming a continuation of said aperture, a strainer carried by the nipple, and means for holding a container for gas under 35

pressure in gas-tight relation with said socket piece so as to deliver the gas through the strainer to the aperture.

2. An anæsthetizing machine comprising 40 an apertured support, a socket piece held by said support and providing through the same a continuation of said aperture, a nipple removably carried by the socket piece and forming a continuation of said aperture, 45 a strainer carried by the nipple, means for holding a container for gas under pressure in gas-tight relation with said socket piece so as to deliver the gas through the strainer to the aperture, a reduced-pressure chamber, 50 means for admitting and controlling the admission of gas from said aperture into the reduced-pressure chamber, and a relief valve having connection with the reduced-pressure chamber whereby the maximum pressure of gas going to said delivering means is 55 determined.

3. An anæsthetizing machine comprising an apertured support, a socket piece removably carried by said support, said socket 60 piece having a flanged head formed with a corrugated plane face, a cylindrical nipple removably carried by said socket piece, said nipple and socket piece forming a continuation of the aperture, and said nipple providing a holder for a container for gas under pressure, and a strainer formed across the nipple.

In testimony whereof we affix our signatures.

JAY A. HEIDBRINK.
BURT J. CLARK.
